UNITED STATES PATENT OFFICE.

WILLIAM F. GOODWIN, OF METUCHEN, NEW JERSEY, ASSIGNOR TO HIMSELF,
JAMES T. SANFORD, AND GEORGE W. SANFORD, OF NEW YORK CITY.

IMPROVEMENT IN PROPELLING BOATS ON CANALS.

Specification forming part of Letters Patent No. 98,760, dated January 11, 1870.

To all whom it may concern:

Be it known that I, WILLIAM F. GOODWIN, of Metuchen, county of Middlesex, State of New Jersey, have invented certain new and useful Improvements in Canal-Boats, of which the following is a full, clear, and exact description, reference being had to the accompanying drawing making part of this specification, in which—

Figure 1 is a plan or top view; and Fig. 2 is a longitudinal section taken in the line *y y*, Fig. 2.

Similar letters of reference denote corresponding parts in both figures.

My invention has for its object the construction of a canal-boat, and the combination therewith of a propelling-wheel, driven by power located on the boat, adapted, as a whole, to obviate the washing of the banks of the canal—a difficulty heretofore experienced in the numerous attempts to propel canal-boats in this manner. To this end my invention consists in constructing the boat in the form of a scow, with the sides made straight and parallel, and projecting, at the forward end, in advance of the body of the boat sufficiently to inclose the propelling-wheel, which is made to float upon the surface of the water, moving or vibrating upon or around the driving-shaft as a center, the arrangement being such that the entire body of water to be displaced by the boat is inclosed between the forwardly-projecting sides, and is, by the operation of the propelling-wheel, forced underneath the body of the boat.

In the accompanying drawings, *A* represents the body of the boat, which is made with a flat bottom and straight parallel sides *A*¹, and with the ends *A*² made curved or inclined, or having the "rake" ordinarily designated as a scow. At the forward end of the boat the sides *A*¹ project sufficiently to inclose the floating propelling-wheel, as shown at *A*³, said projecting ends *A*³ being made of uniform or nearly uniform width or depth with the sides, and united at their upper faces, in front of the wheel, by a cross-piece or beam, *a*. *B* is the propelling-wheel, which is made in the form of a hollow air-tight drum or barrel, of any suitable material, and is provided, on its periphery, with paddles *b*, of any suitable form and depth, the

V-form represented being, however, considered best adapted to prevent any outward swell and the washing of the banks referred to. The wheel *B* is designed to float lightly and freely on the surface, and has its shaft connected, by radial arms *C*, with hubs or sleeves surrounding the main driving-shaft *D* in such manner that all movement of the wheel, in conforming to the surface of the water, independently of the boat, shall be around said shaft as a center, thereby avoiding any disturbance in the working relations of the driving mechanism. The arms *C* work in boxes or water-tight compartments *E* at the sides of the boat, which permit the requisite play of said arms to accommodate the wheel to the varying depth to which the boat may be laden.

The wheel *B* is represented as being driven from shaft *D* by means of chains *F* and sprocket-wheels *d d* on shaft *D*, and *d' d'* on the shaft of the propelling-wheel *B*; but any suitable arrangement of gearing may be used for the purpose.

In the drawing I have represented the sides *A*¹ of the boat as extending in rear of the "rake" of the stern and terminating in a vertical end, and also as extending slightly below the bottom of the boat; and this construction is believed to be of service in further assisting to prevent outward swell and washing of the banks of the canal. Any convenient power may be used for propelling the shaft *D* and wheel *B*.

The operation is as follows, viz.: Motion being imparted to the wheel *B* in the direction indicated by the arrow, Fig. 2, the water inclosed between the projecting ends *A*³ of sides *A*¹ is forced underneath the body of the boat and the boat is drawn forward, causing the projecting ends to continuously receive and inclose the water to be displaced. The water in turn is continuously forced under the boat and escapes at the stern, and in such manner as to avoid all washing of the banks incident to the employment of the various constructions heretofore used.

Having now described my invention, what I claim as new, and desire to secure by Letters Patent, is—

1. A canal-boat having straight sides, which extend from end to end the full length of the boat and project in front of the rake or closed end thereof sufficiently to inclose a propelling-wheel located in front of the bow of the boat.

2. A floating propeller-wheel, traveling in front of the boat for the double purpose of drawing the boat and displacing the water by driving it under the bottom.

3. The floating propeller-wheel connected by hinged arms with the driving-shaft in such manner as to move around or vibrate upon said shaft as a center.

WM. F. GOODWIN.
